AUSTIN F. JACKSON, OF TAUNTON, MASSACHUSETTS, ASSIGNOR TO THE
REED & BARTON CORPORATION, OF SAME PLACE.

DESIGN FOR A SPOON.

Design No. 19,488, dated December 17, 1889.

UNITED STATES PATENT OFFICE.

AUSTIN F. JACKSON, OF TAUNTON, MASSACHUSETTS, ASSIGNOR TO THE REED & BARTON CORPORATION, OF SAME PLACE.

DESIGN FOR A SPOON.

SPECIFICATION forming part of Design No. 19,488, dated December 17, 1889.

Application filed October 21, 1889. Serial No. 327,721. Term of patent 14 years.

To all whom it may concern:

Be it known that I, AUSTIN F. JACKSON, of Taunton, in the county of Bristol and State of Massachusetts, have invented and produced a new and original Design for the Handles of Spoons, Forks, Knives, Ladles, and Kindred Articles, of which the following is a specification, reference being had to the accompanying drawings, forming a part thereof, in which—

Figure 1 is a front view, and Fig. 2 a back view, of a spoon having its handle configured and ornamented according to my design.

The leading feature of my design consists in the representation on the face and back of the handle, about midway between the ends thereof, of convoluted figures A and B, the former on the face and the latter on the back of the handle-strips a and b, leading up, respectively, from said figures A and B. The representation of strip a extends diagonally across the handle and meets and is practically merged at its upper end in the representation of a leaf-like strip C, which extends from the edge of the convoluted figure A up along the edge of the face of the handle, around the end thereof, and terminates in the representation of a scroll C' at one side of the upper end of the handle. The representation of a strip D, having its edge given the appearance of being ruffled or wrinkled, is produced along the inner side of the strip-like representation C. Along the edge of the face of the spoon, opposite the rib C, is produced the representation of rib-like strips E E', the outer representation E extending down along the edge of the handle-face until it meets the representation a, at which end it curves slightly outward. The representation E' extends down for a short distance parallel with E, and then diverges inward, leaving a triangular space, in which is produced the representations F of flowers of the pansy type.

Below the representation A the handle is ornamented at the opposite sides by leaf-like representation G, below which appear the representations of longitudinal ribs, which extend down to the end of the handle. Leaf-like figures g g are represented as lapsing the representation G from the opposite edges of the face of the handle.

On the back of the handle the representation b is given a leaf-like appearance.

Along the edge of the handle, opposite the representation b, is produced a rib-like representation H, which extends up to the top of the handle and terminates in a scroll h, below which is produced the representation I of a leaf, a leaf-like representation being produced across the representation H below the scroll h, and a rib-like representation J, with a leafy representation j crossing it, being produced down along the edge of the handle opposite the representation H. Below the convolution B is produced centrally a leaf-like representation K, at opposite sides of which are produced the representations L L of leaves, below which extend leaf-like representations to the lower end of the handle.

The edge configuration or outline shape of the handle is clearly shown in both the Figs. 1 and 2.

What I claim is—

1. In a design for a spoon, &c., the front side or face of the handle, substantially as shown.
2. In a design for a spoon, &c., the rear side of the handle, substantially as shown.
3. The design for the ornamentation of the handle of spoons, &c., substantially as shown.

AUSTIN F. JACKSON.
